UNITED STATES PATENT OFFICE.

MILLER WILCOX AND HENRY DAY RYAN, OF MORAVIA, NEW YORK.

RAILWAY-TIE.

SPECIFICATION forming part of Letters Patent No. 793,755, dated July 4, 1905.

Application filed September 15, 1904. Serial No. 224,601.

To all whom it may concern:

Be it known that we, MILLER WILCOX and HENRY DAY RYAN, citizens of the United States, residing at Moravia, in the county of Cayuga, State of New York, have invented certain new and useful Improvements in Railway-Ties; and we do hereby declare the following to be a full, clear, and exact description of the invention, such as will enable others skilled in the art to which it appertains to make and use the same.

This invention has relation to metallic railway-ties; and it has for its object the provision of a strong and durable tie and one that will be elastic to a desired degree and possessing other qualities that will obviate the objections heretofore raised to the use of metallic ties.

It is also the object of the invention to provide a chair which will operate to secure the rail more firmly in position than heretofore.

In the drawings forming a portion of this specification, and in which like numerals of reference indicate similar parts in the several views, Figure 1 is a top plan view showing a railway-tie provided with braces and portions of rails. Fig. 2 is a side view of the same. Fig. 3 is an end view of the same. Fig. 4 is a bottom view of the same. Fig. 5 is a detail perspective view of a rail-brace.

In carrying out our invention we propose to employ sheet-steel of proper thickness and to construct the tie in parts, uniting them to form the tie in a way suitable to meet its needs.

We show in the drawings forming a part of this specification and describe a tie and rail-chair embodying our invention at the same time.

We recognize the fact that the form and arrangement of parts may be varied and our invention may still be embodied therein. We will, however, for the sake of clearness and brevity confine our description quite closely to the form shown, which fully embodies the invention.

In the drawings the tie is shown as composed of two parts of sheet-steel, the divisional line running longitudinally of the tie.

The upper face 10 for the reception of the chair 11 is made flat, and this flat portion is

supported centrally and longitudinally by a vertical web 12, which is connected with and forms a part of the hollow base 13. The margin of the meeting portions of the base are 55 slit, as at 14, and the ends of clips 15 are passed through said slits and bent over and pressed or riveted down to hold the two edges together, and the webs 12 are riveted together by rivets 16 passed through the 60 matching holes made through the web, and these latter rivets may be as frequent as thought necessary.

While the bottom of the tie is shown as rounded, it may be made quite flat in some, 65 if not all, cases.

The chair 11 is formed from two pieces of sheet-steel, the base 17 of each piece being made flat, so as to be bolted, as at 18, to the flat top of the tie, and each piece at its inner 70 edge is bent upwardly and inward, as at 19, so as to fit upon the flange forming the base of the rail. (Not shown.) In addition to this a vertically-arranged extension 20 at the middle of the base 17 of each piece is made at 75 its inner edge to bear against the opposite side of the web of the rail for substantially its entire width. To further stay the chair and maintain it in place, we rivet a plate 21 on the end of the tie, with its inner edge bent 80 to overlap the outer edge of the base 17, as shown. The whole forms a durable and safe chair for sheet-metal ties and one that is calculated to hold the rails safely in place.

The feature of elasticity of the tie herein-before referred to is acquired by formation of the tie of sheet metal and giving it the shape illustrated, it being of course understood that the tie will of necessity be slightly flattened when weight is applied thereto and 90 will return when the weight is removed.

What is claimed is—

1. A sheet-metal tie for railways constructed of two parts, each part having a flat upper face, a vertical web and an enlarged 95 bulging base, the two parts being arranged together and the edges of the base united by clips and rivets or bolts binding together the webs of the two parts.

2. A sheet-metal tie for railways constructed of two parts, each part having a flat upper face, a vertical web, and an enlarged 100

bulging base, the two parts being arranged together and the edges of the base united by clips and rivets or bolts binding together the webs of the two parts combined with a chair 5 formed from sheet metal and bolted on the upper flat face, as described and shown.

3. A sheet-metal tie having an upper flat face-plate, a vertical web composed of two thicknesses of metal below the face-plate, 10 and an enlarged hollow base, all of the parts being securely connected, substantially as set forth.

4. An elastic metallic railway-tie formed of two oppositely-curved plates united along their longitudinal edges and rail-securing 15 means fastened to the upper portion of the tie above said meeting edges.

In testimony whereof we affix our signatures in presence of two witnesses.

MILLER WILCOX.
H. DAY RYAN.
